DESIGN FOR AN INFANT'S COMMODE

John H. Moeller, San Francisco, Calif.

Application November 30, 1946, Serial No. 135,198

Term of patent 14 years

(Cl. D4—5)

To all whom it may concern:

Be it known that I, John H. Moeller, a citizen of the United States, residing at San Francisco, State of California, have invented a new, original, and ornamental Design for an Infant's Commode, of which the following is a specification, reference being had to the accompanying drawing, forming a part thereof.

Fig. 1 is a top plan view of an infant's commode showing my new design.

Fig. 2 is a bottom plan view of the infant's commode of Fig. 1.

Fig. 3 is a side elevational view showing the infant's commode of Figs. 1, 2 in extended position.

Fig. 4 is a side elevational view showing the infant's commode of Fig. 3 in collapsed position.

Fig. 5 is a top plan view of the infant's commode with a cover in position thereon.

Fig. 6 is a side elevational view of the infant's commode of Fig. 5 in collapsed position.

I claim:

The ornamental design for an infant's commode, as shown.

JOHN H. MOELLER.
